UNITED STATES PATENT OFFICE

2,507,759

HINGE

George E. Dath, Mokena, Ill., assignor to W. H. Miner, Inc., Chicago, Ill., a corporation of Delaware

Application February 10, 1945, Serial No. 577,292

4 Claims. (Cl. 16—128)

1

This invention relates to improvements in hinges for swinging doors or closures.

One object of the invention is to provide a hinge structure for swinging doors comprising co-operating hinge strap and butt members pivotally connected to each other, wherein the parts are held assembled and pivotally interlocked when the hinge structure is in place on the door and door frame.

A more specific object of the invention is to provide a hinge comprising strap and butt members having cooperating hinge eye and pin portions, wherein the hinge pin portion is formed integral with one of said members, and the other member is composed of a pair of superimposed interlocked sections having the eye portions formed partly on each section and embracing the hinge pin to operatively secure said hinge members together when the sections are interlocked.

A further object of the invention is to provide a hinge structure, as set forth in the preceding paragraph, wherein the parts of the sectional member are maintained in their interlocked relation by the usual hinge securing elements for mounting the hinge in place.

Other objects of the invention will more clearly appear from the description and claims herein-after following.

In the drawing forming a part of this specification, Figure 1 is a broken elevational view of a portion of one of the walls of an automobile truck provided with swinging doors, illustrating my improved hinge in connection therewith. Figure 2 is a plan view of the improved hinge illustrated in Figure 1, on an enlarged scale. Figure 3 is a plan view of one of a pair of plate elements, which together form the butt member of my improved hinge. Figure 4 is a plan view of the other plate element of the pair forming the butt member. Figure 5 is a plan view, partly broken away, of the strap member of my improved hinge. Figures 6, 7, and 8 are horizontal sectional views, corresponding respectively to the lines 6—6, 7—7, and 8—8 of Figures 3, 4, and 5. Figure 9 is a horizontal longitudinal sectional view, corresponding substantially to the line 9—9 of Figure 2.

In said drawing, 10 indicates a portion of one of the walls of the body of an automobile truck provided with a door opening 11, closed by a pair of hinged doors 12 and 13.

As shown in the drawing my improved hinge comprises broadly a hinge leaf or strap A secured to the door; a hinge pin B formed integral

2

with the strap; and a two part sectional hinge leaf or butt C secured to the door post.

The hinge strap A is in the form of an elongated flat plate having the usual screw receiving openings 14—14 for attaching the hinge. At the inner end, the strap A is laterally enlarged or widened, as indicated at 15, said widened portion being cut out or recessed, as indicated at 16, thus providing two laterally spaced, parallel tongues 17—17.

10 The hinge pin B, which is formed integral with the strap A, comprises an elongated, cylindrical member, extending transversely of the strap at the extremities of the tongues 17—17, being rigidly secured to the latter, preferably by being welded to the end edges of said tongues. As shown most clearly in Figure 5, the pin B spans the opening 16 and projects beyond the opposite sides of the widened inner end portion 17 of the strap A.

20 The sectional hinge strap or butt C comprises a pair of superimposed, substantially flat plates 18 and 19. As shown in the drawing, the plate 19 is superimposed upon the plate 18, the latter thus forming a back plate member, and the former a front plate member of the composite hinge butt C. The plates 18 and 19 are of substantially rectangular outline and of the same size, being of greater width than length. When the plates 18 and 19 are secured together by fastening the

25 hinge butt in place, they are in true registration. The plate 18 is provided at its inner edge with a plurality of hook-shaped part eye portions 20, which are preferably three in number and equally spaced apart transversely of the plate. The

30 spaces between the part eyes 20—20—20 are of such a size that the tongues 17—17 fit freely therein with sufficient clearance to permit free swinging movement of the hinge strap with respect to the hinge butt. The plate 19 is pro-35 vided at its inner edge with a part eye member 21, which is in the form of a curved channel. The curvature of the part eye member 21 is re-40 verse to that of the part eye members 20. Adjacent the part eye member 21 of the plate 19, 45 elongated slots or openings 22—22—22 are pro-50 vided which are spaced so as to accommodate the hook-shaped eye portions 20—20—20 of the plate 18.

The plate 19 is superimposed on the plate 18 55 with the part eye portions 20—20—20 of the plate 18 engaged through the openings 22—22—22 and extending over the channel shaped eye portion 21 of the plate 19. The hinge pin B is embraced between the eye portions 20 and 21 of the plates 18 and 19, thus connecting the strap A and the

hinge butt C for pivotal swinging movement. The plates 18 and 19 are provided with aligned openings 23—23 which extend therethrough, adapted to receive the usual headed securing elements 24, which may be in the form of rivets or screws, for securing the hinge butt C, comprising the plates 18 and 19, to the door post or frame. As will be evident, when the hinge is mounted in position on the door and door post, the securing elements 24 for the hinge butt C serve to clamp the plates 18 and 19 together, thereby maintaining the parts of the hinge in their assembled relation.

I claim:

1. In a hinge, the combination with a hinge strap having an integral hinge pin member; of a hinge butt comprising superimposed front and back plates secured together by fastening elements extending therethrough; and a hinge eye portion formed on each plate, the hinge eye portion of said respective plates together forming a complete hinge eye surrounding said hinge pin, the hinge eye portion of said back plate extending in front of the hinge eye portion of the front plate and engaging over the front side of the pin, and said eye portion of the front plate engaging the rear side of the pin.

2. In a hinge, the combination with a hinge strap having an integral hinge pin; of a hinge butt comprising superimposed front and back plates secured together by fastening elements extending therethrough; and a hook-shaped part hinge eye portion formed on each plate, the hook-shaped hinge eye portion of said back plate extending in front of the hinge eye portion of the front plate, said hooked hinge eye portions embracing the hinge pin at opposite sides to pivotally connect the strap and butt.

3. In a hinge, the combination with a hinge strap having an integral hinge pin; of a hinge butt comprising superimposed front and back plates secured together by fastening elements extending therethrough; a hook-shaped part

hinge eye portion formed on said front plate, said front plate being slotted adjacent said eye portion; a plurality of hook-shaped hinge eye portions formed on said back plate extending through the slots of the front plate into overlying relation with and in front of said eye portion of the front plate, said hook-shaped portions of the front and back plates embracing the hinge pin of the strap, thereby pivotally connecting the hinge strap and butt.

4. In a hinge, the combination with a hinge strap having an integral hinge pin; of a hinge butt comprising superimposed front and back plates secured together by fastening elements extending therethrough; a hook-shaped part hinge eye portion of channel formation on said front plate, said front plate having openings therethrough adjacent the eye portion thereof; and a plurality of hook-shaped part hinge eye portions formed on said back plate extending through the openings of the front plate into overlying relation with and in front of said eye portion of the front plate, said eye portions of said front and back plates embracing the hinge pin, thereby pivotally connecting the strap and butt.

GEORGE E. DATH.
